(57) **CLAIM**

The ornamental design for a collapsible helmet, as shown and described.

DESCRIPTION

FIG. 1 is a top, front perspective view of a collapsible helmet, showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top, front perspective view thereof with an unclaimed light inserted therein shown in broken lines;
FIG. 9 is a bottom, rear perspective view thereof with an unclaimed light inserted therein shown in broken lines;
FIG. 10 is a top, front perspective view of a collapsible helmet in an alternate position (a collapsed position) than that shown in FIGS. 1-9;
FIG. 11 is a front view of a collapsible helmet in the alternate (collapsed) position;
FIG. 12 is a rear view of a collapsible helmet in the alternate (collapsed) position;
FIG. 13 is a left side view of a collapsible helmet in the alternate (collapsed) position;
FIG. 14 is a right side view of a collapsible helmet in the alternate (collapsed) position;
FIG. 15 is a top view of a collapsible helmet in the alternate (collapsed) position;
FIG. 16 is a bottom view of a collapsible helmet in the alternate (collapsed) position;
FIG. 17 is a top, front perspective view of a collapsible helmet in the alternate (collapsed) position with an unclaimed light inserted therein shown in broken lines; and,
FIG. 18 is a bottom, rear perspective view of a collapsible helmet in the alternate (collapsed) position with an unclaimed light inserted therein shown in broken lines.
Any broken lines showing portions of the design are to show environmental structure or boundaries that form no part of the claimed design.

1 Claim, 16 Drawing Sheets
